FERDINAND A. SCHAEFER, OF BALTIMORE, MARYLAND

GRAVITY ACTUATED TENSION REGULATOR FOR DRAWING PRESSES

Application filed December 22, 1928. Serial No. 328,025.

This invention relates to an attachment to presses to provide uniformity of initial tension on a blank or strip while being drawn and formed. It enables a number of cups or 5 deep depressions to be made simultaneously on a single strip, it includes a process for use in deep drawing and punching.

Heretofore when metal was drawn in presses, rubber pads or springs, or other 10 means had to be employed on the pressure ring or blank holder to iron out the drawn metal and prevent wrinkling or cracking. Since the pressure of these devices increased 15 with the compression of the rubber or spring, it was found necessary to employ compensating attachments, which were both complicated and unsatisfactory.

Uniformity in pressure was sought in order 20 to insure proper flow of metal in the drawing operation. But this result could not be attained because frictional resistance was depended on to govern the drawing of the metal. And, as is well known, friction varies 25 not only with the character and condition of the surfaces, but with the time they have remained in contact and with the speed. Moreover, kinetic friction is usually double static friction. So, it is obvious that any 30 means depending on frictional resistance might be uncertain in its action. There can be no uniformity in the flow of metal to a die as long as the flow is governed by friction.

It is evident that the flow of metal is dependent, not on the constancy of the pressure exerted on the blank, but on the uniformity of the resistance that blank or strip offers to the drawing action and the strength 40 of this resistance. It is only when the pull of the drawing die overcomes the resistance offered to such pull by the blank or strip, that there can be any flow of metal. The accurate regulation of this resistance and its 45 uniformity is the crux of the problem.

I obtain the desired uniformity in the resistance the blank or strip offers to the drawing action of the die by entirely eliminating frictional resistance and substituting therefor what I term constant initial tension. I 50 place the blank or strip under tension before

the punching and drawing takes place by flexing a portion of it adjacent to the portion to be punched, taking care to leave the flexed portion free to be pulled back to its original plane, by the drawing action of the die or dies, overcoming the initial tension caused by the flexing. 55

It will be seen that the invention consists broadly in regulating the flow of metal to the dies in deep drawing by placing the strip or blank under constant initial tension by means of flexing the strip or blank by exerting pressure thereon. The novelty consists broadly in substituting such constant initial tension for frictional resistance. The invention is not limited to any specific form of die or blank or manner of supporting the blank on the die or pressure means of flexing the blank. For instance, any means of exerting pressure known to those skilled in the art or now used in compensating devices on friction rings may be used for this purpose by applying such pressure means directly to the surface of the blanks. Thus any such equivalent means of exerting pressure to flex the blanks may be substituted for the weights illustrated in the drawings. 70 75

I am thus not only able to dispense with reliance on friction, but I am able to dispense also with the pressure ring formerly used to regulate the drawing of metal. By 80 my novel use of constant initial tension I am able to regulate accurately as well as insure uniformity in the flow of metal in deep punching and drawing. 85

I provide simple gravity actuated means to take up the slack of the strip or blank and keep it under the uniform tension desired, and am thus enabled to use a single acting press carrying a number of punches and dies 90 to form and draw simultaneously in one operation on a single strip the desired number of cups or depressions.

By my invention the limitations and disadvantages due to the use of friction rings or 95 other customary means of regulating the flow of metal to dies are avoided and the drawing of metal accurately regulated by the amount of flexing which governs the constant initial tension of the blank or strip. 100

The flexing can be accurately regulated by the pressure exerted on the portion of the blank to be flexed. After clamping the flexed blank or strip in adjusted position in relation to the die or dies, as soon as the drawing action overcomes the resistance offered by the constant initial tension of the blank, metal is drawn from the flexed portion and the flexure correspondingly decreased.

10 In the drawings illustrating one embodiment of my invention Fig. 1 is a side elevation view of the punch bed and attachments.

Fig. 2 is a plan view of the same looking up.

15 Fig. 3 is a side elevation view of the die beds and attachments.

Fig. 4 is a plan view of the same looking down.

20 Fig. 5 is an end elevation view of the punch bed and attachments.

Figs. 6, 7 and 8 are detailed views of the parts of a die.

25 The punch bed 3 is provided with the three punches 1 which are riveted to the block or bolster 2. The stud 5 connects the punch bed to the ram of the press (not shown). The two spindles 6 carrying the weight 7 move vertically in their bearings on the punch bed 3. The shearing punches 8 at the 30 two ends of the punch bed cut the strip to the desired length, and serve to hold the sheared strip as flexed in adjusted position in relation to the punch and die. The punch block 2 is fastened to the bed 3 by the screws 4.

35 The die bed 11 carries the three dies 9 which are riveted to the block or bolster 10 which is screwed on to the die bed. These dies are made in three parts of different lengths as shown in Figs. 6, 7 and 8, the 40 smaller fitting in and being riveted to the larger.

The strip can be automatically fed into the press with sufficient slack to enable three cups to be drawn on the strip. The slack is taken 45 up by the pressure of the spindles which depress the strip at the points of contact, until the drawing action of the punches takes up the slack, causing the weights to rise. Thus the tension on the strip is kept constant as 50 the weights lift and the strip is sheared at the desired length of band.

The manner of operation is as follows—

55 The strip (not shown in drawings) is fed automatically to lie over the die bed 11, portions resting freely on the faces of the three dies 9, with intermediate portions of the strip unsupported and free to move vertically downward, the end of the strip projecting beyond the shearing edge of the die 8.

60 The spindles 6, free to move in their bearings, vertically with the weights 7 which they support, come into contact, as the ram is lowered, with the underlying portion of the strip lying midway between the dies, 65 pressing down on such portion and flexing

the strip until the resistance of the strip balances the pressure or the lowest point of flexure takes up against the die bed 11. The amount of this flexure can be accurately controlled by the resiliency of the strip, the weight and the height of the face of the die above the top of the die bed.

70 The shearing edges of the end punches 1 cut the flexed strip to the desired length, as the punches register with the dies, gripping the flexed strip in adjusted set position and by overcoming initial tension of the strip draw the metal.

75 Preferably a flat thin resilient blank or strip is used so anyone susceptible of flexing can be employed in my invention. It is essential that the blank be mounted on the die so that it can freely flex on the application of pressure on its surface. Then by clamping the strip or blank beyond the flexed portion the constant initial resistance caused by the flexure will regulate the flow of metal.

80 This means of keeping the strip to be punched and drawn under constant pressure can be utilized wherever it is desired to form on a single strip a number of cups or depressions requiring drawing the material of the strip.

85 My invention can also be utilized on a single blank and punch and die, by having the 90 weights press down on the free edges of the blank, as is shown by dispensing with the end punches and dies shown in the Figures 1 to 5 of the drawings.

95 Nor is my invention limited to weights operated on spindles bearing downward on the blank. Obviously the pressure on the edges of the blank could be exerted by any weight or other equivalent means of exerting pressure suitably controlled, exerting either 100 downwards or upwards pressure on the portion of the blank. All that is essential for punching a plurality of cup-like depressions on a strip, is that a portion of the blank be sufficiently displaced or temporarily deformed upwards or downwards from the flat 105 surface of the blank to provide enough slack metal to enable such portion to provide necessary metal for the drawing operation, the 110 moment the pull of the drawing operation overcomes the pressure exerted by the gravity actuated means. The tension can be regulated 115 and varied as well as the amount of slack metal taken up to suit the special needs, by regulating the size of the weights or other equivalent means of exerting pressure, and the distance the blank or strip can be displaced, before it takes up against the die or 120 punch bed.

I claim:

125 1. The combination for simultaneously stamping and drawing on a single acting press a plurality of depressions on an integral strip of sheet metal, said combination comprising of a plurality of drawing punches 130

and a corresponding number of drawing dies, the punches and dies being adapted and positioned on their respective holders to register with each other and one or more gravity actuated means intermediate each pair of punches or dies for maintaining the strip at a uniform tension during the stamping and drawing process.

2. A multiple punch and die for simultaneously stamping and drawing the end and middle portions of an integral strip of sheet metal, comprising of two shearing and drawing punch and die members and midway thereon a third drawing punch and die mem-

ber and a gravity actuated means intermediate each pair of punch and die members for maintaining the strip at a uniform tension during the stamping and drawing process.

3. A multiple punch and die for simultaneously stamping and drawing the end and middle portions of an integral strip of sheet metal comprising of two registering, shearing and drawing punch and die members and midway on the strip a third registering, drawing and punch member and a gravity actuated member intermediate each punch member, said member consisting of a weight, a spindle carrying the weight, slidably mounted on a punch holder, the end of the spindle pressing and supported on the strip of metal, whereby the strip is kept under uniform pressure during the stamping and drawing process.

4. A method of drawing and deeply punching a flat sheet metal blank in one operation on a drawing press, consisting in first exerting pressure by gravity actuated means on a portion capable of vertical movement of the blank lying in adjusted position on a die bed, whereby such portion is displaced or temporarily deformed, then subjecting another portion of the blank to the drawing and punching operation, whereby the displaced portion can supply sufficient slack metal for the drawing process, while the blank is continually held under uniform tension by the constant pressure of the gravity actuated means.

5. A method of regulating the drawing of metal in deep punching by subjecting the blank to uniform tension comprising flexing a portion of the blank adjacent to the portion to be punched to perpendicular pressure exerted by gravity means, then securing the flexed blank in adjusted position for the action of the die whereby the drawing action must overcome the uniform initial tension before there is any flow of metal.

6. The process of drawing metal without utilizing frictional resistance comprising slightly flexing by pressure a portion of the blank, clamping the blank so flexed in set position for drawing and punching whereby the flexure is maintained and the blank kept under uniform predetermined initial tension

by the pull exerted by the flexure, then subjecting the blank to the action of the punch, drawing metal from the flexed portion as soon as the drawing action overcomes the uniform initial tension, whereby the metal required to supply the deep drawing is drawn.

7. The process of drawing and deforming a portion of a flat resilient strip comprising curving by pressure perpendicular to its plane, a portion of this strip within its elastic limits, then clamping the strip in set position on a die, then punching the blank, adjacent to the curved portion into the shape desired, whereby the drawing action of the punch reduces the curvature and thereby the extra material required in deep punching is supplied.

8. The process of drawing and deeply punching a portion of a metallic blank, comprising flexing by gravity means, the central portion of the blank, a predetermined amount, then clamping the margin of the flexed blank, then subjecting a portion of the blank lying in approximately the original plane of the blank, to the punching and drawing action whereby the pressure of the gravity means is overcome, and the flexed portion is drawn toward the punch portion, supplying a flow of extra metal to the die.

9. The process of drawing and deeply stamping a section of a flat metallic blank, lying horizontally on the face of a die, consisting in flexing the section of the blank by direct downward pressure of a weight free to move vertically, then clamping the flexed blank in set position, whereby the blank remains under constant predetermined tension, then subjecting the blank to the drawing action of the stamping.

10. The process of drawing and punching a blank having a flat central portion and slightly curved, resilient marginal portions comprising resting the flat portion on the face of a die, projecting from the die bed, clamping the edges of the portion so curved in set position on the press, so that the edges rest in the plane of the die, and the flat portion lies in adjusted position in relation to the punch and die, then subjecting the flat portion of the blank, to the punching action of the die, whereby its drawing action is governed by the resistance offered by the curved portion to straightening.

11. The method of regulating the drawing of metals in deep punching and stamping by means of placing the surplus metal under uniform initial tension, which method comprises flexing by perpendicular pressure on its surface a portion of a flat blank by gravity means, free to move vertically, then securing the flexed blank in set adjusted position, for deep punching and drawing, whereby the drawing pull of the punch must overcome the constant contrary tension of the blank,

and the resistance offered by the gravity means to any decrease in flexure, before there is any flow of metal.

12. The process of punching and drawing a plurality of deep cups on a metal strip comprising resting the strip on the face of a plurality of spaced dies, then, by exerting pressure perpendicular thereto, flexing the strip intermediate the dies, then performing the drawing and cupping, whereby the drawing pull exerted by the dies overcomes the pressure on the strips and metal is drawn to the dies.

13. In a drawing press provided with a die and punch, means of supporting the securing on the press a flat slack blank in adjusted position, whereby a portion of the blank is left free to move perpendicularly to its plane, and pressure means for moving the free portion of the blank perpendicularly to form a curved portion, whereby the slack of the blank is taken up and the blank kept under constant initial tension.

14. In a press provided with a die and punch for deep punching, means for supporting in its plane a portion of a flat resilient blank, gravity means for flexing an unsecured portion of the blank, together with means for clamping the flexed blank in set position in relation to the punch and die, whereby the blank is kept under constant tension until such tension is overcome by the drawing action.

15. A method of regulating the flow of material from a flexible blank to a drawing press comprising supporting the blank in adjusted position for the drawing operation so that the blank contacts only with a face of the die or punch, and with an outlying portion of the drawing press, then flexing by pressure means the unsupported portion of the blank adjacent the die, then clamping the outlying contact of the blank, before subjecting it to the drawing action of the die.
